IMPROVEMENT IN MELTING FURNACES.

SAMUEL A. WHITNEY, OF GLASSBORO, NEW JERSEY.

Letters Patent No. 60,307, dated December 4, 1866.

SPECIFICATION.

TO ALL WHOM IT MAY CONCERN:

Be it known that I, SAMUEL A. WHITNEY, of Glassboro, Gloucester county, New Jersey, have invented an improved Melting Furnace; and I do hereby declare the following to be a full, clear, and exact description of the same, reference being had to the accompanying drawing, and to the letters of reference marked thereon.

My invention consists of a furnace, constructed in the peculiar manner fully described hereafter, for the purpose of obtaining a more intense heat by the concentration of the products of combustion, and for the purpose of so distributing the latter that the crucibles shall be uniformly heated throughout, thereby preventing their fracture, and at the same time economizing the consumption of fuel.

In order to enable others skilled in the art to make and use my invention, I will now proceed to describe its construction and operation.

On reference to the accompanying drawing, which forms a part of this specification,

Figure 1 is a vertical sectional view of my improved furnace;

Figure 2, a sectional plan of the same, on the line 1 2, fig. 1;

Figure 3, a section of part of the furnace on the line 3 4, fig. 2;

Figure 4, a detached sectional view on the line 5 6, fig. 1;

Figure 5, an outside view of part of the furnace; and

Figure 6, a sectional view of part of an ordinary glass furnace.

Similar letters refer to similar parts throughout the several views.

The lower portion, A, of my improved furnace is, in the present instance, circular, and has two opposite fire-places, B and B', each of which is provided with an ordinary door, *a*, grate bars, *b*, and ash pit, *c*, and with each ash pit communicates a blast opening, *d*. (See fig. 1.) Each fire-place has an inclined top, as shown in fig. 1, and a passage, *e*, through which it communicates with a central vertical flue, *C*. At right angles to the fire-places, and extending through the lower portion A of the furnace, is an arched tunnel, *D*, above which, and beneath the flue *C* is formed a reservoir, *E*, the latter, as seen in fig. 4, communicating with the tunnel *D* through a small opening, *f*, the object of which will be rendered apparent hereafter. The lower portion A of the furnace supports a circular superstructure, *F*, of fire-proof material, the peculiar shape of which will be best observed on reference to fig. 1. This dome-like superstructure has a central chamber, *C'*, forming a continuation of the central flue *C*, and terminating in the arched roof *g*. On the bed of the furnace within the dome a number of pots or crucibles, *G*, (eight in the present instance,) are arranged in a circle, and at equal distances apart from each other, each crucible resting on small projections, *x*, and at points between the crucibles the wall surrounding the chamber *C'* is pierced with holes, *h h*, (figs. 2 and 3.) Passages, *H*, communicating with the central flue *C*, are formed beneath the bed of the furnace and directly under each crucible, in front of which each passage has an outlet, *i*. Around the side of the dome are openings, *m*, one opposite each crucible, the openings being separated by the triangular supports *I*, in each of which is formed an outlet flue, *l*. Each of these openings, *m*, is closed, as seen in fig. 1, by removable slabs, *n*, of fire clay, and in the dome *F*, immediately over each of the said openings, *m*, are cut ring-holes, *p*, (fig. 5.) Supported by columns, *q q*, and above the dome *F*, is a conical chimney, *X*, shown in red lines, fig. 1. The crucibles with the material to be melted are introduced through the openings *m* into the furnace, and are so adjusted as to rest upon the projections *x*, by means of which the crucibles are elevated sufficiently to permit the products of combustion to pass beneath them. After the introduction of the crucibles, the openings *m* are entirely closed by means of the slabs *n*, shown in fig. 1, the ring-holes *p* in the dome being left open.

The fuel being kindled, the products of combustion, accelerated by the blast through the openings *d*, pass in the direction of the arrows, fig. 1, through the fire-places B and B', and the passages *e e*, into the central flue *C*, into the chamber *C'*, and thence through the flues *H* and openings *h* into the chamber containing the crucibles.

In order to explain the advantages of my improved glass furnace, it will be necessary to refer to one of ordinary construction, as seen in fig. 6. In this furnace, the products of combustion rise to the top of and are dispersed and expanded throughout the interior of the high dome, and then take a downward course towards the ring-holes *p*. By their expansion, the heat of the products of combustion is diminished; the crucibles, moreover, are unevenly heated, the products of combustion impinging against the rear of each crucible, while the front is comparatively cool, an evil which results in their frequent rupture. In my improved furnace, the space for the reception of the crucibles is contracted as much as possible, partly by depressing the dome at the

top, as seen in fig. 1, and partly by the walls round the circular chamber C, thus leaving a contracted annular chamber, within which the crucibles are arranged in the manner described. Instead of permitting the products of combustion to expand after leaving the fire-place, they pass first into the contracted flue C, thence into the chamber C', from which they are distributed through still more contracted openings, H and h, into the annular chamber containing the crucibles. So intense is the heat caused by this concentration and distribution of the products of combustion, that no unconsumed particles of the latter pass into the crucible chamber, hence the most pure flint glass can be melted in open pots. It will be seen that the outlet flues for the passage of the products of combustion into the crucible chamber are so arranged, in respect to the crucibles, that an uniform heat must be imparted to every portion of the latter; even the bottoms of the crucibles receive their proper degree of heat, as they rest on projections, so that the products of combustion can pass beneath them. The flues l are generally closed at the top by slabs, a', which, however, may be occasionally removed, should it be desirable to cause a portion of the products of combustion to pass off without rising into the crucible-chamber. Should any molten glass escape from the crucibles, it will find its way through the passages H h into the central flue, and fall thence into the recess E, from which it will flow through the passage f into any suitable receptacle within the tunnel D.

Although I have illustrated and described my improved glass furnace as being circular in form, it will be evident that the main features of my invention may be carried out in a furnace of oval, oblong, or other modified shape. The furnace may also be used for melting steel and other metals in crucibles.

I claim as my invention, and desire to secure by Letters Patent—

1. A furnace composed of the lower portion A, containing the fire-places and central flue, C, and the super-structure containing the central-chamber C' and crucible chamber, communicating with each other through contracted passages, all substantially as described.
2. The combination and arrangement, substantially as described, of the central distributing chamber C', passages H h, and crucible chamber G'.
3. The projections x, arranged as a support for the crucibles, substantially as and for the purpose described.
4. The dome-shaped structure, F, depressed in the middle and arranged to cover the central chamber C' and crucible chamber G', in the manner and for the purpose specified.

In testimony whereof, I have signed my name to this specification, in the presence of two subscribing witnesses.

S. A. WHITNEY.
